Attorney

UNITED STATES PATENT OFFICE.

W EARL SNYDER, OF NORWOOD, OHIO, ASSIGNOR TO THE EDNA BRASS MFG. COMPANY,
OF CINCINNATI, OHIO, A CORPORATION OF OHIO.

LUBRICATOR.

Application filed September 29, 1924. Serial No. 740,437.

To all whom it may concern:

Be it known that I, W EARL SNYDER, a citizen of the United States, and residing at Norwood, in the county of Hamilton and

5 State of Ohio, have invented a new and useful Lubricator, of which the following specification is a full disclosure.

This invention relates to the art of lubrication, and is particularly directed to 10 improvements in lubricators of the condensation displacement type, which ordinarily are provided with an upper condensation chamber into which the steam is admitted, a lower oil reservoir in communication at its 15 bottom with the bottom of the condensation chamber, and various passages communicating with the oil chamber having nozzles for delivering oil vertically therefrom into separate delivery passages and thence to the 20 parts to be lubricated. A valve controlled water passage connects the condensation chamber with the oil reservoir through which water is introduced from above to a point at or near the bottom of the oil reservoir, and this passage is controlled by a 25 manually operable valve.

It frequently happens that the attendant 30 closes the water valve preparatory to filling the lubricator with oil, and inadvertently leaves the same closed, with the result that when the engineer subsequently turns on the steam the oil in the oil reservoir is expanded by the heat, and equalization of the pressure being impossible, creates an 35 undue pressure in the oil chamber, resulting in deformation or fracture of the same.

The main object of the invention is, therefore, to provide an automatically operable 40 valve controlling a passage connecting the condensation chamber and oil reservoir in such manner that the pressure in the oil reservoir under the conditions above mentioned may be relieved or equalized, and for this purpose the auxiliary automatically operable valve is made to open toward the 45 condensation reservoir.

A further object of the invention is to 50 provide a specific construction and placement of the valve for the above purpose, providing a by-passage communicating with a portion of the water passage which connects the bottom of the condensation chamber with the bottom of the oil reservoir, whereby automatic equalization or relief of

the pressure in the oil chamber is obtained 55 whenever, through inadvertence, the water valve remains closed when the steam is turned on.

Other features relate to the specific construction of the valve and its placement 60 within the condensation chamber as a prolongation of a portion of the valve controlled water passage, from which position it is conveniently accessible for attachment or 65 removal.

Other objects and certain advantages will appear in the description of the drawings forming part of the specification, in which:

Figure 1 is a vertical transverse section 70 through a condensation displacement lubricator showing the placement of the valve for equalizing the pressure between the condensation and oil chambers.

Figure 2 is a longitudinal section of the 75 valve.

Figure 3 is a cross section of the same on line 3—3, of Fig. 2.

Figure 4 is a reduced section on line 4—4, Fig. 1.

The present invention is adapted to automatically relieve the pressure in the oil chamber thereby counter-acting the evil effects incident to the admission of steam to the lubricator when the water valve is closed, the herein disclosed means for accomplishing the result being in the nature of a pressure equalization device placed at an intermediate point between the chambers.

The condensation lubricator shown is of a commercial type and comprises a body or 90 casing 1, providing an oil reservoir 2 at its upper portion, herein of globular configuration, from which the oil is adapted to be displaced by water of condensation delivered to the reservoir at or near its bottom through 95 a water passage formed in the following manner:

The upper part of the main casing has a passage 5 extending laterally therefrom and downwardly at one side forming a first 100 blind passage leading out of the condensation chamber. A second passage 6 leads laterally from the blind passage, into a third passage 7 parallel with the downwardly directed portion of the first, which third passage leads to a point adjacent the bottom of the oil reservoir, the passage thus formed connecting both reservoirs. The third pas-

sage lies vertically, is substantially parallel with the delivery passage 5, and is herein represented as a bore traversing a projection at the side of the tube forming an oil 5 delivery passage and traversing the oil reservoir. A check valve casing 10 as a prolongation of the third passage 7 extends from its upper end into the condensation 10 reservoir and this casing is of tubular construction in threaded engagement at one end and in communication with the passage 7 and has radial openings 11 at an intermediate point, leading to the condensation 15 chamber. The tube is interiorly threaded at its upper end to receive a spring adjusting plug 12. The valve 13 has the form of a cylinder, is slidable within the casing, and has radial centering fins 14 extending lengthwise thereof, providing passages 16 and further has a cone-shaped seating end 15 engageable with the periphery of a small opening 16 extending through the otherwise closed lower end of the casing. A spring 20 is interposed between the upper end of the 25 valve and the spring adjusting plug.

The condensation casing or chamber 25 is of bulblike configuration, is separately formed, and detachably secured in vertical position at the top of the casing, vertically over the oil reservoir, and has at its top a valve 26 for controlling a steam inlet 27. A series of equalization tubes 28 connect the chamber with respective vertical water-filled oil delivery conduits or passages 29, the water in this condensation chamber lying approximately at the level of the upper ends of the tubes, a steam space being thus provided thereabove.

Sight glasses are arranged in diametric relation with respect to the ends of the delivery nozzles 31, and the nozzles at their lower ends have seats concentric with the passages with which engage the end of an oil regulating valve 37.

The oil is introduced into the reservoir 2, through a filling opening (not shown) at the top of the casing 1, and is forced by water of condensation delivered through the passage 7, from the top of the oil reservoir 2 downwardly through a conduit, in the form of the pipe 40 which extends to and communicates with a horizontally disposed general cross delivery channel 30 located at the lowest point of the main casing. From points along this channel the oil is delivered under pressure upwardly through removable vertically disposed nozzles 31 extending into the similarly disposed delivery pipes 29, the oil passing through the nozzles and water of condensation in the pipes. The water level within these vertical pipes or conduits 29 is approximately maintained at that of the choked passage of the delivery pipes 35 extending horizontally from the upper part of the casing above the oil

chamber, through which pipes the mixed oil and steam is delivered and thus distributed to the parts to be lubricated.

Steam is delivered through the equalization pipes and comes in contact with the surface of the liquid in the oil delivery passages, the pressure throughout the apparatus thus being equalized at all points.

The water conduit above described also normally permits equalization of pressures between the two chambers, this passage, as before mentioned, connecting the bottom of the condensation chamber with the bottom of the oil reservoir, an intermediately disposed manually operable valve being provided for controlling the water flow between the two chambers as desired.

When the lubricator is in operation, the water valve should be set as shown in Fig. 1, but as frequently happens this valve is closed while the oil reservoir is being filled and steam pressure subsequently turned on, with the result that super-pressure is created within the oil reservoir and the walls are either deformed or fractured.

The conditions under which expansion and fracture of the oil chamber ordinarily take place, are when during cold weather oil is introduced into the reservoir, and the steam subsequently turned on with the water valve closed, this notwithstanding that the oil chamber may only have been partially filled. Under these conditions with the oil in cold and contracted condition an unusual expansion takes place when heat is applied.

Having described my invention, I claim:

1. A condensation lubricator including a condensation chamber and oil reservoir having a water passage connecting the same for delivery of water from one chamber to another, a valve for closing the water passage, a second valve for automatically controlling the passage when the water valve is closed, said valve opening toward the condensation reservoir to relieve pressures in the oil chamber.

2. A condensation displacement lubricator including a condensation chamber and oil reservoir having a passage connecting said chamber and reservoir, and a manually operable valve for closing the water passage, a second valve for independently automatically controlling the passage when the water valve is closed, said valve adapted to be opened by pressure to establish communication between the oil reservoir and condensation chamber to relieve the pressures in the oil reservoir.

3. A condensation displacement lubricator including a condensation chamber and oil reservoir having a passage connecting the same, a manually operable valve for controlling the passage, and a check valve for independently controlling said water passage, when said first mentioned valve is closed,

adapted to open the passage from the oil reservoir to the condensation chamber to relieve pressure in said oil chamber.

4. A condensation displacement lubricator including a passage connecting the condensation chamber and oil chamber, a valve for controlling the passage, and a by-passage independently connecting the two chambers, having a pressure operable valve therein adapted to open toward the condensation chamber, as result of super-pressures in the oil chamber.

5. A condensation displacement lubricator having a water passage connecting the condensation and oil chambers, a valve for controlling the water passage, and a by-passage independently connecting the two chambers, having a check valve therein adapted to open to the condensation chamber to relieve pressure in the oil chamber when the first mentioned valve is closed.

6. A condensation displacement lubricator having a water passage connecting the condensation and oil chambers, and a manually operable valve for controlling the passage, an auxiliary passage independently establishing communication between the chambers, and a check valve in said second passage, normally closing the same and adapted to be opened as the result of super-pressure in the oil chamber, when the first mentioned valve is closed, to prevent fracture of the oil chamber.

7. A condensation displacement lubricator

having a water passage connecting the bottom of the condensation chamber with the bottom of the oil reservoir, a manually operable valve for controlling said passage, a by-passage as an extension of the water passage independently connecting the condensation chamber with the oil reservoir side, said passage having a check valve therein normally closed and adapted to be opened by super-pressures in the oil chamber, when the manually operable valve is closed.

8. A condensation displacement lubricator having a passage leading laterally, then downwardly from the bottom of the condensation chamber, closed at its lower end, a second passage adjacent the first leading from the bottom of the conduit chamber to a point adjacent the bottom of the oil chamber, a cross passage connecting the first and second passages at a point intermediate the chamber, a manually operable valve for controlling the cross passage, a valve casing forming a prolongation of the second passage within the condensation chamber having a check valve therein, for closing the lower end of the casing and second passage, and adapted to be opened by super-pressures in the oil chamber, when the cross passage is closed by its valve.

In witness whereof, I hereunto subscribe my name.

W EARL SNYDER.
